CARTRIDGE

John V. Rice, Jr., Philadelphia, Pa.

Application November 13, 1941, Serial No. 418,883

18 Claims. (Cl. 102—56)

This invention relates to cartridges, and has reference more especially to cartridges of a type having hollow projectile heads which contain explosive charges whereby said heads are shattered at some time during their flight or when the objective is encountered.

My invention has for its chief aim to increase the destructive potentiality of cartridges of the kind referred to without adding to the liability of accidental discharge incident to ordinary handling.

This desideratum I attain in practice as hereinafter more fully disclosed, through provision of means whereby, as the cartridge is fired, a quantity of air or other gas trapped within the projectile head, is highly compressed and raised to a correspondingly high temperature, and subsequently released for access to the explosive charge in the head at some time during the flight of said head or as a consequence of impact with a solid object in its path.

Other objects and attendant advantages will appear from the following detailed description of the attached drawings, wherein

Fig. 1 is a fragmentary view in longitudinal section showing the barrel of a gun with the cartridge of my invention in position therein ready to be fired.

Fig. 2 is a view similar to Fig. 1, showing the cartridge at the time of firing with the projectile head thereof detached from its body and advancing in the barrel of the gun.

Fig. 3 is a view in turn like Fig. 1 showing the projectile head of the cartridge or shell after it has left the barrel of the gun and encountering a solid object.

Fig. 4 is a detail view in cross section taken as indicated by the angled arrows IV—IV in Fig. 3; and

Fig. 5 is a view like Fig. 1, showing a regulating auxiliary means in connection with the projectile head, which can be pre-set to determine the time of bursting of said head after leaving the gun.

With more specific reference first more particularly to Figs. 1-3 of these drawings, it will be seen that my improved cartridge comprises a hollow body component or shell 1 which is cylindric and of a diameter to snugly fit the bore of the gun barrel 2, being closed at its rear end as at 3 and there formed with a circumferential stop flange 4. The capacity of the body component 1 is such as to hold a suitable firing charge of gun powder which is conventionally indicated at F and which is adapted to be detonated by

means of a priming or percussion cap or the like 5 set into the closed rear end of said body. The cartridge further comprises a projectile head 6 which is axially aligned with the body component, and like the latter is of generally cylindric configuration and snugly fits the bore of the gun barrel 2. At its rear end, the projectile head 6 is releasably connected by means of a relatively fine screw 7 with the contiguous end of the body component 1, its front end being rounded off in a manner characteristic of projectiles. Fitting into a rearwardly open bore 8 in the projectile head 6 is a piston 9 which is normally positioned at the rear end of said bore immediately forward of the firing charge F within the body component as shown in Fig. 1, the space in front of said piston containing free air or other gas at atmospheric pressure. The piston 9 can move forwardly within the bore 8, but restricted against retrograde movement by an annular series of balls 10, which, through the wedging action of the sloping surface of a groove 11 of triangular cross section peripherally of said piston and under the influence of an annular spring 12, are maintained in effective gripping engagement with the bore wall. At the front end of the projectile head 6, see Figs. 1, 2 and 4, is an impact element 13 having a central rearward projection 14 which extends into a small axial bore 15, and a number of rearwardly projecting annularly arranged plungers 16 which snugly fit into correspondingly allocated hollows or bores 17. At their inner ends, the hollows or bores 17 terminate in an annular port 18 which is normally closed by a valve 19 whereof the reduced stem 20 extends outwardly into the bore 17. A relatively light spring 21 reacting upon an enlargement 22 at the outer end of the stem 20 serves to normally keep the valve 19 in closed position as shown in Figs. 1 and 2. For a reason to be later explained, a considerable interval is left between the inner end of the projection 14 on the impact element 13 and the corresponding end of the valve stem 20. In practice the hollows or bores 17 are filled with a secondary charge of explosive which may either be a volatile hydrocarbon or nitroglycerine.

By detonation of the firing charge F in the body 1 of the cartridge, the piston 9 is forcibly advanced in the bore 8 of the projectile head 6 as shown in Fig. 2, with the result that the trapped gas or air ahead of said piston is highly compressed and its temperature raised to a correspondingly high degree. Concurrently, by the force of the explosion, the fine thread conne-

tion at 7 is ruptured with consequent detachment of the head 6 from the body 1 of the cartridge, likewise as shown in Fig. 2, the piston being held in its advanced position by the checking action of the wedge balls 10. In this condition the projectile head 6 is forcibly ejected from the barrel of the gun 2 by the expanding explosion gases, as illustrated in Fig. 3. Upon encounter of the impact element 15 with a solid object O as in Fig. 3, the projection 16 and the plungers 18 are forced inwardly within the respective bores or hollows 17 and 19. As a consequence the secondary explosive charges in the cavities 19 are first compressed, and this is soon followed by encounter of the projection 16 with the stem of the valve 21 which latter is thereby opened against the pressure of the spring 23 as is also shown in Fig. 3. As the highly compressed and highly heated air or gas thus released from the bore 8 meets with the highly compressed charges of explosive in the hollows or bores 19, said charges are set off to instantaneously and effectively shatter the head and the parts associated therewith. Under this novel principle of ignition of the explosive charges in the projectile head, it will be apparent that a maximum destructive effect is obtained from the cartridge. On the other hand, in its normal condition with the piston 9 retracted as shown in Fig. 1, my improved cartridge is safe against the danger of accidental or premature firing thereof even if roughly handled ordinarily. It is also to be noted that the simplicity of its construction is favorable to very economic manufacture in quantity at small cost.

In the modification illustrated in Fig. 5, the projectile head 6a is reduced and threaded at its forward end as at 25 for connection of a cap 26 whereof the front end is rounded off, projectile fashion. As shown the cap 26 completely surrounds the outer end of the impact element 15a; and disposed within it, immediately to the front of the element 15a, is a stout helical compression spring 27. The end of the spring 27 adjacent the element 15a abuts against a spider 28 with radial arms, which, at the outer ends, bear against a narrow peripheral shoulder 29 internally of the cap 26. Slidably fitting into an axial bore 30 at the nose end of the cap 26 is a plunger 31 which has a reduced rearward axial stem 32 extending through a correspondingly reduced portion 33 of said bore, said stem also passing through a central aperture in the spider 28, and terminating short of the impact element 15a. At its inner end, the stem 32 is formed with an enlargement 35 which acts as a stop for the spider 28. In practice the space behind the piston 31 in the bore 30 is filled with a non-freezing liquid such as oil, and from the inner end of said bore extends a lateral duct 36 which is normally closed by a screw pin valve 37. As shown, a branch duct 38 leads at an angle rearward from the enlarged portion of the duct 36 to the outer surface of the cap 26. Prior to placement of the cartridge into the gun, the screw 37 is backed off slightly to allow bleeding of the oil from the bore 30 through the duct 36 and the branch duct 38. Upon firing of the cartridge of Fig. 5, the piston 9a is forcibly urged forward exactly as in the first embodiment and compresses the air or gas ahead of it within the bore 8a. During the flight of the projectile head 6a after it leaves the gun barrel, the small plunger 31 is slowly moved rearwardly in the bore 30 by the spring 27 as the oil bleeds through the duct 36 and its branch 38 with

the result that eventually the spider 28 is suddenly broken down by the force of said spring and the latter released to exert its energy upon the impact element 15a, incident to which the explosive charges in the cavities 19a are first compressed and the valve 21a soon thereafter opened to permit the previously compressed hot air or gas to meet said charges and to explode them.

Instead of employing oil in the bore 30 behind the plunger 31 in Fig. 5, there may be substituted a slow burning powder with a suitable fuse accessible from the exterior of the head of the cap 26, and adapted to be ignited just before the cartridge is placed in the gun. The piston 9a is in this instance made hollow as at 40 and filled with a powerful explosive such as TNT. This explosive is introduced through a central opening 41 at the front end of the piston 9a, which opening is sealed by a soft metal plug 42 of lead or the like. As further shown in Fig. 5, the valve 20a is provided with a central pointed rearward projection 43 in line with the seal 42. Thus as the valve 20a is opened, the pointed projection 43 pierces the seal 42 and allows access of the highly compressed and highly heated air or gas to the charge of explosive within the piston 40 at the same time that access thereof is established to the smaller charges in the cavities 19a of the projectile head.

It is of course to be understood that if desired, the last described feature may be incorporated in the first embodiment of Figs. 1-4 to augment the destructive potentialities of the cartridge there shown.

Having thus described my invention, I claim:

1. A cartridge having a body component containing a firing charge; a projectile head releasably-connected to the body component and having two separate hollows, one containing a gas, and the other containing an explosive charge; means within the head operative upon explosion of the firing charge to highly compress the gas within the head concurrently with forcible detachment of said head from the body component and projection of said head into space; and means associated with the head and subsequently operative to automatically bring about access of the highly compressed gas to the explosive charge in the head to set off said charge.

2. A cartridge having a body component containing a firing charge; a projectile head releasably-connected to the body component and having two separate hollows, one containing a gas, and the other containing an explosive charge; means within the head operative upon explosion of the firing charge to highly compress the gas within the head concurrently with forcible detachment of said head from the body component and projection of said head into space; and means associated with the head and subsequently operative to first compress the explosive charge in the head and to later bring about access of the highly compressed gas to the explosive charge in said head to set off said charge.

3. A cartridge having a body component containing a firing charge; a projectile head releasably-connected to the body component and having two separate hollows, one containing a gas, and the other containing an explosive charge; means within the head operative upon explosion of the firing charge to highly compress the gas within the head concurrently with forcible detachment of said head from the body component and projection of said head into space; and means associated with the head and subsequently oper-

ative to automatically release the highly compressed gas into the explosive charge in the head to explode said charge; and means capable of being pre-set to determine the time of release of the gas.

4. A cartridge having a body component containing a firing charge, a projectile head releasably-connected to the body component and having two hollows or cavities, one containing a gas, and the other containing an explosive charge; means within the head operative upon explosion of the firing charge to highly compress the gas within the head concurrently with forcible detachment of the head from the body component and projection of said head into space; and means associated with the head and operative upon encounter of the head with a solid object to bring about access of the hot compressed gas to the explosive charge in said head to shatter said head.

5. A cartridge including a hollow body component containing a firing charge, an elongated projectile head releasably-connected to the body component, said head having a lengthwise bore at the rear in communication with the hollow of the body component and containing a gas, said head also having a cavity in the front end thereof containing an explosive charge; a normally closed valve covering a port between the bore and cavity of the head; a piston with means for restricting it to forward movement in the bore of the head, said piston normally occupying the rear of the bore immediately in advance of the firing charge in the body component and being operative upon explosion of said firing charge to highly compress the gas within the head concurrently with forcible detachment of said head from the body component and projection of said head into space; and means associated with the head and subsequently operative to automatically open the valve for access of the highly compressed gas to the explosive charge in said head to set off said charge.

6. A cartridge according to claim 5, in which the piston is hollow and itself contains an explosive charge; and further including means associated with the head for exploding the charge in the piston concurrently with setting off of the explosive charge in the head.

7. A cartridge according to claim 5, in which the means for restricting the piston to forward movement in the head comprises a peripheral groove of triangular cross section in said piston, and an associated spring pressed member adapted to be wedged against the wall of the piston bore by the sloping surface of said groove.

8. A cartridge including a hollow body component containing a firing charge; an elongated projectile head releasably-connected to the body component and having a lengthwise bore at the rear in communication with the hollow of the body component, containing a gas, said head also having a cavity in its forward end containing an explosive charge; a normally closed valve covering a port between the bore and cavity of the head; a piston with means for restricting said piston to forward movement in the bore of the head, said piston normally occupying the rear of the bore immediately in advance of the firing charge in the body component and being operative upon explosion of said firing charge to highly compress the gas concurrently with forcible detachment of said head from the body component and projection of said head into space; and means

associated with the head and subsequently operative to first compress the explosive charge in the head and later to automatically open the valve for access of the highly compressed gas to the explosive charge in said head.

9. A cartridge including a hollow body component containing a firing charge; an elongated projectile head releasably-connected to the body component and having a lengthwise bore at the rear in communication with the hollow of the body component, containing a gas, said head also having a cavity in its forward end containing an explosive charge; a normally closed valve covering a port between the bore and cavity of the head; a piston with means for restricting said piston to forward movement in the bore of the head, said piston normally occupying the rear of the bore immediately in advance of the firing charge in the body component and being operative upon explosion of said firing charge to highly compress the gas concurrently with forcible detachment of said head from the body component and projection of said head into space; an impact element normally extending beyond the front end of the head, said element having a rearward plunger projection extending into the cavity containing the explosive charge and a rearward projection extending into a bore in the front of the head with the inner end of said rearward projection normally spaced from the valve whereby, upon impact of said element with a solid object, the explosive charge in the head is first compressed and the valve later opened for access of the highly compressed air to said explosive charge to set off said charge.

10. A cartridge according to claim 9, in which the piston is hollow and contains an explosive charge; and further including means whereby the charge in the piston is set off when the valve is opened.

11. A cartridge according to claim 9, in which the piston is hollow and contains an explosive charge, and further including a displaceable seal for normally retaining the explosive charge within the piston; and means whereby the seal is punctured when the valve is opened.

12. A cartridge according to claim 9, in which the piston is hollow and contains an explosive charge, and further including a displaceable seal for normally retaining the explosive charge within the piston and a projection on the valve for puncturing the seal when said valve is opened.

13. A cartridge including a hollow body component containing a firing charge; an elongated projectile head releasably-connected to the body component and having a lengthwise bore at the rear in communication with the hollow of the body component, containing a gas, said head also having a cavity in its forward end containing an explosive charge; a normally closed valve covering a port between the bore and cavity of the head; a piston with means for restricting said piston to forward movement in the bore of the head, said piston normally occupying the rear of the bore immediately in advance of the firing charge in the body component, and being operative upon explosion of said firing charge to highly compress the gas concurrently with forcible detachment of said head from the body component and projection of said head into space; a spring, and means for normally holding the spring in compression within the head; and timing means capable of being set to subsequently release the holding means and thereby allow the spring to open the valve for access

of the highly compressed gas to the explosive charge in the head.

14. A cartridge including a hollow body component containing a firing charge; an elongated projectile head releasably-connected to the body component and having at the rear in communication with the hollow of the body component, a lengthwise bore containing a gas, said head also having a cavity in its forward end containing an explosive charge; a normally closed valve covering a port between the bore and cavity of the head; a piston with means for restricting said piston to forward movement in the bore of the head, said piston normally occupying the rear of the bore immediately in advance of the firing charge in the body component and being operative upon explosion of said firing charge to highly compress the gas concurrently with forcible detachment of said head from the body component and projection of said head into space; a cap attached to the front end of the head; a spring; means for normally holding the spring in compression within the cap; and timing means capable of being set to subsequently release the holding means and thereby allow the spring to open the valve for access of the highly compressed gas to the explosive charge in said head.

15. A projectile having two separate hollows, one containing a gas and the other containing an explosive charge; means associated with the projectile operative upon firing of the projectile from a gun to highly compress the gas; and means also associated with said projectile and subsequently operative to automatically bring about

access of the highly compressed gas to the explosive charge to set off said charge.

16. A projectile having two separate hollows, one containing a gas and the other containing an explosive charge; means associated with the projectile and operative upon firing of the projectile from a gun to highly compress the gas; and means also associated with said projectile subsequently operative to first compress the explosive charge and to later bring about access of the highly compressed gas to said charge to set it off.

17. A projectile having two separate hollows, one containing a gas and the other containing an explosive charge; means associated with the projectile and operative upon firing of the projectile from a gun to highly compress the gas; means associated with the projectile and subsequently operative to automatically release the highly compressed gas into the explosive charge to set it off; and means also associated with said projectile capable of being pre-set to determine the time of such release.

18. A projectile having two hollows or cavities, one containing a gas and the other containing an explosive charge; means associated with the projectile and operative upon firing of the projectile from a gun to highly compress the gas; and means also associated with the projectile and operative upon encounter of the projectile with a solid object to bring about access of the compressed gas to the explosive charge to shatter the projectile.
